UNITED STATES PATENT OFFICE

KENNETH H. LEASH, OF OAKLAND, CALIFORNIA, ASSIGNOR TO H. E. LEASH, OF OAKLAND, CALIFORNIA

WINDMILL

Application filed February 3, 1932. Serial No. 590,528.

This invention is a windmill and has special reference to an automatically actuated folding or shutter vane windmill in which the vanes are automatically presented 5 to the wind on one side of the windmill and which swing free in the wind on the other side thereof.

The main object of the invention is to provide a windmill of high efficiency and which 10 will operate with slow moving air currents.

Another object of the invention is to provide a windmill of the character described which will automatically free all of the vanes under abnormal wind pressures.

15 A further object of the invention is to provide mechanical means for releasing the vanes to prevent operation of the windmill.

Other objects and advantages of the invention will become apparent as the following 20 description is read on the drawings forming a part of this specification and in which similar reference characters are used to designate similar parts throughout the several views and in which:

25 Fig. 1 is an elevation of the invention with front arm removed.

Fig. 2 is a section taken on line 2—2 of Fig. 1.

Fig. 3 is an enlarged sectional elevation 30 taken on line 3—3 of Fig. 4.

Fig. 4 is a plan view of the invention.

Fig. 5 is a fragmentary sectional view showing the vane retarding means, and is taken on line 5—5 of Fig. 1.

35 Fig. 6 is a fragmentary view showing the center connection for the arms.

The invention consists of a windmill having a plurality of radial arms or frames each of which consists of a triangular frame 40 formed of structural shapes such as angles 10 and 11 which at their inner ends are connected to a horizontal arm 12, from which the angles diverge outwardly, the outer ends 45 being connected to a tubular pivot member 13 which coincidentally forms a spacer, and is secured to the angles 10 and 11 by means of U bolts 14.

Tubular members 15 are also secured to the 50 angles 10 and 11 by means of U bolts 14 and

coincidentally form spacers, pivot members and housings for the latch mechanism.

Tubular members 16 are similarly secured to the members 10 and 11 and form spacers and latch housings, as also a support for the 55 retarding vanes, and has intermediately secured thereto as at 17 one end of the horizontal arm 12, the other end being mounted in a block 18 which is pivotally secured to the head 19 by means of a shouldered screw 60 20, which permits pivotal movement of the arms in a vertical plane.

Guy wires or cross bracing 21 connects opposite ends of adjacent arms, the bracing being secured together at the point of crossing as shown at 22. The ends of the bracing are so positioned as to permit the vanes to 65 pass through.

The arms are mounted on wheels 23 which are preferably mounted on ball bearings, 70 supported on a shaft 24 which is supported by a bracket 25 secured to member 11 and a bracket 26 secured to the lower extension of the pivot member 15, a circular track 27 being provided for the wheels. 75

It will be noted that a rigid structure is thus produced which is supported by the wheels 23 which are located substantially at the vertical center of gravity of the arms, and that the wind pressure on any arm and its 80 vanes are evenly distributed through the cross bracing 21 to all arms, thence through the horizontal arms 12 to the head 19, which is fixedly secured to the top of the central or drive shaft 28.

Vanес 29 are mounted on the tubular members 13 by means of hinges 30, members 13 serving as a pintle, the vanes being adapted to swing clear around, and through the opening between members 10, 11, 13 and 15. 85

Vanес 31 are similarly mounted to vanes 29 and are adapted to pass between members 15 and 16 and also between members 15 and 13.

The latch mechanism consists of a plurality of stops 32 consisting of pins secured in weights 33 which are slidable in the tubular members 15 and 16, slots 34 in the pipes permitting limited vertical movement of the latches, the weights being secured in spaced 100 105

relation by adjustable members 35. Slots 36 in the vanes clear the latches when the latches are raised.

The automatic releasing mechanism for the latches consists of a vane 37 secured to the upper end of a bell crank lever 38 which is intermediately pivoted at 39 to a bracket 40 which is secured to the member 10, the other end of lever 38 having an adjustable connecting link 41 pivotally secured thereto as at 42, the other end of the link being pivotally attached to the string of weights as at 43.

The manual releasing mechanism for the latches consists of a lever 44 which is intermediately pivoted at 45 and cooperates with a collar 46 which is rotatable on the shaft 28 and has an annular groove 47 adapted to cooperate with pins 48 which are secured in a block 49 which is slidable within the shaft 28, slot 50 permitting longitudinal movement of the pins.

A link 51 is slidably mounted in the block 49 and has a stop element 52 secured at the lower end. A connecting link 53 is attached at one end to the link 51 and has attached to the other end a plurality of flexible elements 54, one for each vane arm, which are individually guided by sheaves 55, the sheaves being mounted in upward extensions 56 of the head 19, the flexible elements being attached to the levers 38 as indicated at 57 and in such position as to successively release the vanes 29 and 31.

Retarding means is provided for the inner vane or vanes in each frame for the purpose of preventing the inner vane from opening in advance of the outer vane and thereby locking the outer vane in closed position, which would readily occur in the event of slight sticking of the outer vane on its hinged support. Should the inner vane, when the windmill is in the position in which the vane is in the tail wind, open previous to the opening of the outer vane, it would obviously swing about and prevent the outer vane from opening. For this reason, the retarding vane 58 is provided and is applicable to any number of vanes in series, merely by using retarding vanes having different projecting areas for the different vanes whereby one of the retarding vanes will retain the cooperating hinged vane in closed position for a longer period than the next adjacent vane.

The retarding vanes are preferably made of arcuate form and cooperate with the free end of the hinged vane in opposition to the latch, and the length of the arcuate portion indicated at 58 in Fig. 5, will determine the wind pressure required on the hinged or main vane to overcome the resistance of the retarding vane 58. These retarding vanes are hingedly mounted in a vertical plane as indicated at 59 and are adapted to swing into contact with the free side of the main vanes.

As is clearly indicated in Fig. 4, as the wind-

mill rotates in a clockwise direction, the retarding vanes 58 are swung about out of cooperative relation to the free end of the vanes 31 and do not cooperate with these vanes until the vanes have reached the position of the arm 64, and thereafter cooperate until the arm has reached the position 65 and beyond this point until the wind reaction on the right hand surface of the vane 31 is sufficient to overcome the reaction on the front face of the retarding vane 58.

From this it will be noted that the retarding vanes are only operative at the point where the main vane is normally intended to open.

It will also be noted that the latch releasing vanes operate only in one direction, and that wind pressure has no effect on their operation in the positions 64, 65 and 66, and that due to their arcuate form, the releasing means can only be operative when they get in the vicinity of the position 63 with the wind blowing in the direction indicated by the arrow in Fig. 4.

For this reason, the releasing vanes are only operative in the region of head wind and in the position where the vane normally closes against the latch. For this reason the latch releasing means is instantly responsive and has no tendency to make the windmill inoperative due to a sudden gust of wind, which would readily occur if all the latches were operated simultaneously, and in addition to this, it is doubtful whether a single releasing means could operate the device in a heavy wind, due to the fact that if all were operated simultaneously, the pressure on the vanes in the position 64 would be too great on the latches to permit the wind actuated vanes to overcome the friction between the latches and the vanes. With my system, the vanes are not called upon to release the latches after the vane has actually come in contact therewith, but actually moves the latch to an inoperative position previous to cooperation with the vane.

The central or drive shaft is rotatably supported in bearings 60 which are mounted on a supporting frame 61, the shaft having suitable transmission gearing 62 for transmitting the power of the windmill to suitable pumps or other appliances.

This windmill is particularly suited for operating pumps for pumping sea water to evaporating ponds, pumping irrigation water and similar purposes.

The operation of the invention is as follows:

With lever 44 released, vanes 37 are all moved to a vertical position as shown in Fig. 1, allowing the latches 32 to engage the doors.

With the wind blowing in the direction indicated by the arrow as shown in Fig. 4, the free ends of the vanes 29 and 31 lodge against the latches 32 in the position of the arm indi-

cated as 63, the wind pressure acting on the vanes in the position 64, and as the arm reaches the position 65, wind pressure on retarding vane 58 prevents vane 31 from swinging open while vane 29 swings to a position in line with the wind. As the arm swings farther about, pressure on vane 58 is overcome by the pressure against the back of vane 31 which is thus released and swings open, both vanes remaining in line with the wind through position 66 to position 63.

It will be noted that when the arm reaches position 65, vane 29 is suddenly swung open followed by vane 31 due to restraint of vane 31 by retarding vane 58. The vanes are then kept with the wind until position 63 is reached when the vanes are closed and retained by latches 32.

When the wind pressure on the releasing vanes 37 becomes great enough to lift the weights 33, the vanes are moved back by the wind when approaching position 63, moving the latches upwardly where they are cleared by the slots 36 which permits the vanes 29 and 31 to freely rotate about the pintles, thus obviating damage by unusually heavy wind.

The device is stopped by pressing down on lever 44 which through the flexible elements 54 raises the latches, these elements being so secured on levers 38 as to first release vane 29 followed by vane 31, so that vanes 29 may be released by placing lever 44 in intermediate position, and still permit operation of vanes 31.

Having described an operative device it will be understood the variations in construction and arrangement of parts which are consistent with the appended claims may be resorted to without detracting from the spirit or scope of the invention or sacrificing any of the advantages thereof.

I claim:

1. A windmill, in combination, a vertical shaft rotatably mounted, a plurality of radially disposed frames pivotally secured to said shaft for vertical pivotal movement, inner and outer vanes swingably mounted on a vertical axis in each of said frames, auxiliary vanes, auxiliary vane actuated stop means for each inner and outer vane adapted to cooperate with one side of said vanes and retarding vanes cooperating with each inner vane to cause the outer vane to open previous to the inner vane.

2. A windmill, comprising a vertical shaft rotatably mounted, a plurality of radially disposed frames secured to said shaft and adapted for vertical pivotal movement, a plurality of vanes swingably mounted on vertical axes in each of said frames, stop means for each vane adapted to cooperate with one side of said vanes, wind actuated and hand operated means for moving said stops out of cooperative relation to said

vanes, and wind actuated means for preventing simultaneous opening of the plurality of vanes.

3. A windmill comprising a vertical shaft rotatably mounted, a plurality of radially disposed frames secured to said shaft for vertical pivotal movement, each of said frames being intermediately supported on rollers, a circular track for said rollers, a plurality of vanes swingably mounted on vertical axes in each of said frames, gravity actuated stop means for each vane adapted to cooperate with one side of said vanes, wind actuated and hand operated means for releasing said latches, and means for causing said vanes to open successively.

4. A windmill comprising a vertical shaft rotatably mounted, a plurality of radially disposed frames secured to said shaft and adapted for vertical pivotal movement, each of said frames being intermediately supported on rollers, a circular track for said rollers, a plurality of vanes swingably mounted on vertical axes in each of said frames, stop means for each vane adapted to cooperate with one side of said vanes, wind actuated and hand operated means for moving said stops out of cooperative relation to said vanes.

5. A windmill comprising a vertical shaft rotatably mounted, a plurality of radially disposed frames secured to said shaft and mounted for vertical pivotal movement, two vanes swingably mounted in each of said frames, gravity actuated stop means for each vane adapted to cooperate with said vanes, hand operated and wind actuated releasing means for said stop means and wind actuated retarding means for certain of said vanes adapted to cause the vanes in each frame to open successively when acted on by the wind.

6. A windmill comprising a vertical shaft rotatably mounted, a head on said shaft, a plurality of triangular frames vertically disposed and secured to said head for vertical pivotal movement by an element connected between the vertex of said frame and said head, intermediately disposed vehicular supporting elements for each of said frames, each frame being divided into sections by three vertical tubular elements, vanes hingedly mounted on the outer and intermediate tubular elements, latches slidably mounted in the inner and intermediate tubular elements, auxiliary vanes hingedly mounted at the top of the inner and intermediate tubular elements and connecting means between said vanes and said latches adapted to raise said latches when said auxiliary vanes are acted on by abnormal wind pressures, and an auxiliary retarding vane hingedly mounted on the inner tubular element and cooperating with the free end of the inner vane in opposition to the latch.

7. In combination with a windmill having a central vertical shaft and a head on the shaft, a plurality of radial triangular frames and rotative supporting means for said frames, vanes hingedly mounted in said frames, and stop means for said vanes, means for connecting said frames to said shaft comprising an arm having one end fixedly secured at the vertex of said frame, the other end being pivotally secured to the head of said shaft on a horizontal axis whereby vertical movement of said frame is permitted.

8. A windmill comprising a vertical shaft, a head on said shaft having a plurality of plane faces parallel to the axis of the shaft, a frame pivotally secured at one end to each of said plane faces to permit pivotal movement of the frame in a vertical plane, a plurality of vanes swingably mounted in each frame, gravity actuated stop means for each vane and wind actuated releasing means for each stop means, a road wheel located substantially at the vertical center of gravity of each arm, the pivotal connection of said frame permitting the weight of said frame to be carried by the road wheel.

9. A windmill comprising a vertical shaft, a head on said shaft having a plurality of plane faces parallel to the axis of said shaft, a frame pivotally secured at one end to each of said plane faces to permit pivotal movement of the frame in a vertical plane, a road wheel for supporting each frame, a plurality of vertically disposed tubular members in each frame, a vane hingedly mounted on each tubular member except one, a gravity actuated stop for each vane, wind actuated releasing means for each stop, hand actuated releasing means cooperating with said wind actuated means, an arcuate retarding vane hinged on said one tubular member in cooperative relation to the free end of the adjacent vane when in closed position, wind pressure on the arcuate retarding vane maintaining the adjacent vane closed beyond the point at which the adjacent vane is normally opened by wind pressure.

50

55

60

65

10. A windmill comprising a vertical shaft rotatably mounted, a head on said shaft, a plurality of triangular frames radially disposed, each of said frames having a single pivotal connection on said head to permit vertical pivotal movement of the frame, a supporting wheel for each frame, a circular track, three vertical tubular members in each frame, a vane hingedly mounted on each of the two outer members, a gravity actuated vane stop slidable in each of the two inner tubular members, a release vane pivotally mounted adjacent each inner tubular member on the top of the frame and having a connection to the stop for raising the stop, hand operated release means, connections between said release vanes and to said hand operated release means, a retarding vane hingedly mounted on the innermost tubular member for cooperation with the free end of the adjacent vane in opposed relation to the stop for retarding the normal opening period of the adjacent vane.

11. A windmill in combination, a vertical shaft, a plurality of radial frames secured at one end to said shaft for vertical pivotal movement, each of said frames being vehicularly supported, two vertically hinged vanes in each frame, individual wind responsive release means for each vane and hand operated means for actuating at will said wind responsive release means.

12. A windmill in combination, a vertical shaft, a plurality of radial frames secured at one end to said shaft for vertical pivotal movement, each of said frames being vehicularly supported, two vertically hinged vanes in each frame, individual wind responsive release means for each vane, hand operated means for actuating at will said wind responsive release means, and wind responsive auxiliary vanes cooperating with the innermost vane in each frame to retard the opening thereof.

In testimony whereof I affix my signature.

KENNETH H. LEASH.
